UNITED STATES PATENT OFFICE.

FRANCIS B. STEVENS, OF NEW YORK, N. Y.

IMPROVED CONDENSER FOR STEAM-ENGINES.

Specification forming part of Letters Patent No. 40,510, dated November 3, 1863.

To all whom it may concern:

Be it known that I, FRANCIS B. STEVENS, of the city, county, and State of New York, have invented a new and useful Improvement Steam-Engines; and I do hereby declare that the following is a full and exact description thereof, reference being had to the accompanying drawings, and to the letters of reference marked thereon.

It has heretofore been proposed to withdraw the steam from the cylinder of a steam-engine by two successive discharges by means of two sets of eduction-valves, the first set opening and closing before the last set commence to open. I will in this specification refer to this action as a "double eduction," and I will call the first of the two successive discharges the "first eduction," and I will call the other discharge the "second eduction."

My improvement consists in simplifying the apparatus that condenses the steam discharged by the first eduction from the cylinder of a condensing steam-engine by closing the hot-well of the engine against the atmosphere, and by keeping a portion of the space of the hot-well free from water, and by delivering the steam discharged from the cylinder by the first eduction into the hot-well, so that it may be condensed or partially condensed by the water delivered by the air-pump into the hot-well. I thus make the hot-well act also as an additional condenser and dispense altogether with an additional air-pump to draw the water from the additional condenser.

This apparatus can be used in connection with a cooler. It then becomes an improved application of the combination of a cooler with a double eduction, which I have described in the specification of an application for a patent bearing even date herewith, or it can be used, when it is desired, to heat the feed-water by the steam discharged from the cylinder by the first eduction.

Figure 1 is a vertical sectional drawing of an application of my improvement.

A is the ordinary or common single-acting air-pump of a condensing-engine.

B is the delivery-valve of the pump.

C is the hot-well, closed against the atmosphere, and having a portion of its space free from water.

D is the pipe leading the steam discharged from the cylinder by the first eduction into the hot-well.

E is the feed-pipe.

F is the pipe for discharging the water from the hot-well into the cooler, this pipe being placed below the level of the feed-pipe.

G is a snifting-valve placed above the level at which the water rises in the hot-well. The air or uncondensed vapor is snifted out of the hot-well through this valve by the compression of this air by the volume of water discharged into the hot-well from the air-pump.

The operation is as follows: The air-pump bucket is represented as being on its upstroke, and the water delivered by the previous stroke of the pump is represented as having fallen to or nearly to the level of the feed-pipe. The water in the air-pump will thus be delivered into a portion of the space of the hot-well that contains only steam or uncondensed vapor, and in falling will be further heated by the steam discharged from the cylinder by the first eduction, by the pipe D, into the hot-well. The pipe F leads the water from the hot-well to the cooler, from whence it is returned to the ordinary or common condenser of the engine. The valve G must be so loaded as to rise when the delivery-valve B rises, and thus snift out the uncondensed vapor or air. A small air-pump placed in the same position as the snifting-valve can be used as an equivalent for it.

If the object in delivering the steam discharged from the cylinder by the first eduction into the hot-well is to heat the feed-water, then the pipe F is not used, but instead the discharge-pipe H (shown in dotted lines) will deliver the water into the atmosphere. This pipe must turn up, as shown, to close the hot-well against the atmosphere, and to prevent air entering the hot-well, and it is represented as delivering the water at a level above that at which the feed-pipe is attached, and the valve G must be so loaded as to rise before there is sufficient pressure in the hot-well for the air or vapor to be blown out through the pipe H.

Fig. 2 is a vertical sectional view of another application of my improvement. The same letters of reference are used as in Fig. 1, but

the form of the hot-well and of the delivery-valve are different from those shown in Fig. 1.

What I claim as my invention is—

1. Condensing the steam discharged from the cylinder of a steam-engine by the first eduction, by delivering this steam into the hot-well of the engine, in the manner herein described.

2. The application and use to, and in the supplying of, a cooler with water heated in the hot-well by the steam discharged from the cylinder by the first eduction, in the manner herein described.

3. In connection with delivering the steam discharged by the first eduction into the hot-well, the arrangement of the pipe for drawing off the water from the hot-well into a cooler, and also the arrangement of the pipe for drawing off the water from the hot-well into the atmosphere, and also the arrangement of the sniffling-valve or its equivalent, in the manner herein described.

FRANCIS B. STEVENS.
